UNITED STATES PATENT OFFICE.

MIKE SLAWIENSKI, OF CAMDEN, NEW JERSEY.

HANDLE ATTACHMENT FOR MOTOR CYCLES.

Application filed March 29, 1923. Serial No. 628,542.

To all whom it may concern:

Be it known that I, MIKE SLAWIENSKI, a citizen of Poland, residing at 38 North 3rd Street, Camden, in the county of Camden, and State of New Jersey, have invented new and useful Improvements in Handle Attachments for Motor Cycles, of which the following is a specification.

My invention relates to new and useful improvements in a handle attachment for motor cycles, and has for its primary object to provide means for maintaining the rotatable grip, which controls the fuel supply or ignition mechanism, and the like, in any desirable adjusted position.

Another object of this invention is to improve the construction and arrangement of devices of like character in order that the handle grip may be rotated with little effort on the part of the operator and in which the wear on the operating parts will be reduced to a minimum.

A further object of my invention is to provide an attachment that may be readily applied or affixed to the handle of motor cycles already in use and having different sized handle bars and grip, such object being accomplished by means of two split rings in which the elements of each are hinged together and fastened about their respective parts by attaching means such as bolts and nuts. One of the split rings is provided with a corrugated portion with which coacts a wheel journalled on a spring actuated lever carried by the other ring.

A still further object of the invention contemplates the provision of means to latch the spring actuated lever in an inoperated position at which time the wheel of the lever will be held out of contact with the corrugated ring.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawing forming a part of this application, in which:

Fig. 1, is a fragmentary perspective view of a motor cycle handle illustrating the application of my invention.

Fig. 2, is an enlarged sectional side elevation of the attachment removed from the handle, and

Fig. 3, is an end view of the corrugated ring.

In carrying out my invention as herein embodied 2 represents a handle of any ordinary or desirable construction as usually employed upon motor cycles and comprises a handle bar 3 with a grip 4 rotatably mounted thereon. In actual practice this grip has connection with suitable mechanism for controlling the ignition, fuel supply and the like.

On the handle bar adjacent the grip is detachably mounted a split ring 5 consisting of a pair of similar substantially semi-circular members 6 and 7 hinged together as at 8 whereby said ring may be opened and closed for detachable connection to the handle bar where it is held in its adjusted position by suitable fastening means 9 such as a bolt and nut or their equivalents. The bolt and nut as a fastening means is preferred and where such is used the former passes through flanges 10 produced on the ends of the ring members opposite the hinge.

The ring 5 is circumferentially corrugated adjacent one end or edge only as indicated by the numeral 11 leaving a plain portion 12 having designation marks thereon such as "1/16", "1/8", etc., to indicate the relative position of the mechanism actuated by the rotatable grip as will be apparent from the later description.

A split supporting ring 14 is adapted for detachable securement to the grip 4 and comprises two similar substantially semi-circular members 15 and 16 hinged together at 17 and held in proper adjusted position by suitable fastening means 18, such as a bolt and nut or their equivalents, with the bolt passing through the flanges 19 produced on the ends of the ring members opposite the hinge.

This supporting ring carries ears 20 for supporting an axle 21, in the form of a short pin, on which are fulcrumed the depending lugs 22 of the lever 23 having one end projecting forwardly to overlie the corrugated ring 5 and on this end of the lever is journalled a wheel 24 for coaction with the corrugations 11 and adapted to normally occupy one of the depressions of said corrugations to maintain the grip in an adjusted position through the medium of the support-

ing ring, the lever and their component parts.

A spring 25 has its body portion coiled about the axle 21, with opposite ends engaging the supporting ring and lever, as the stationary and movable members respectively, to normally force said lever in that direction which will cause the wheel to engage the corrugations.

10 In order to provide for holding the wheel 24 out of contact with the corrugated ring, which is desirable when traveling through congested traffic localities, a latch 26 is slidably mounted on the lever 23 adjacent the 15 rear or operating end and is preferably situated in a slot with the nose of the latch beneath the lever and a push button connected with the latch above the lever so as to be readily operated. This latch is adapted to 20 be moved into cooperative relation with a keeper 27, such as a fixed staple, when the rear or operating end of the lever is depressed and in consequence of which the wheel 24 is raised and disengaged from the 25 corrugated ring. To prevent accidental movement of the latch 26 a small flat spring 28 is fastened to the lever with the free end in engagement with the latch providing sufficient tension to hold the latch in its adjustment.

In practice when running along the less frequented roads the desired position of the grip may be ascertained and then maintained by means of the attachment so that 35 the speed of travel will be uniform and this is particularly desirable when a number of people are traveling together on different machines for if the speed of all is the same they will be constantly side by side.

40 Of course I do not wish to be limited to the exact details of construction as herein shown as these may be varied within the limits of the appended claims without departing from the spirit of my invention.

45 Having thus fully described my invention, what I claim as new and useful is:-

1. A handle attachment for motor cycles comprising, in combination, a corrugated ring for attachment to a handle bar adjacent 50 to the rotatable grip, a supporting ring for attachment to said grip, a spring actuated lever carried by the supporting ring and having one end overlying the corrugated ring, and a wheel journalled on said overlying end for coaction with the corrugated ring to hold the grip in any adjusted position.

2. A handle attachment for motor cycles comprising, in combination, a corrugated 60 ring for attachment to a handle bar adjacent the rotatable grip, a supporting ring for attachment to said grip, a spring actuated lever carried by the supporting ring and having one end overlying the corrugated

ring, a wheel journalled on said overlying end for coaction with the corrugated ring to hold the grip in any adjusted position, and means to hold the lever in such position that the wheel is out of contact with the corrugated ring.

3. The combination with a motor cycle handle including a handle bar and a rotatable grip mounted thereon, of a split ring comprising two similar members hinged together and adapted to be detachably mounted on the handle bar, means engaging said members to hold the ring in its adjusted position, corrugations formed on only a portion of said ring leaving a plain portion for indication marks associated with the corrugations, a split supporting ring comprising two similar members hinged together and adapted to be detachably mounted on the rotatable grip, means engaging the members to hold said supporting ring in its adjusted position, ears projecting from said ring, an axle mounted in said ears, a lever, lugs thereon to fulcrum the lever on the axle, a wheel journalled on one end of the lever for coaction with the corrugated ring and means to force the lever in that direction which will normally hold the wheel in contact with said corrugated ring.

4. The combination with a motor cycle handle including a handle bar and a rotatable grip mounted thereon, of a split ring comprising two similar members hinged together and adapted to be detachably mounted on the handle bar, means engaging said members to hold the ring in its adjusted position, corrugations formed on only a portion of said ring leaving a plain portion for indication marks associated with the corrugations, a split supporting ring comprising two similar members hinged together and adapted to be detachably mounted on the rotatable grip, means engaging the members to hold said supporting ring in its adjusted position, ears projecting from said ring, an axle mounted in said ears, a lever, lugs thereon to fulcrum the lever on the axle, a wheel journalled on one end of the lever for coaction with the corrugated ring, a spring coiled on the axle with its ends in engagement with the supporting ring and lever to force the latter in that direction which will normally hold the wheel in contact with the corrugated ring, a latch slidably mounted on the lever, a spring carried by said lever and engaging the latch to prevent accidental movement of the latter and a keeper on the supporting ring to be engaged by the latch when the lever is positioned to disengage the wheel from the corrugated ring.

In testimony whereof, I have hereunto affixed my signature.

MIKE SLAWIENSKI.
